J. FERGUSON MORSELL, OF STAMFORD, CONNECTICUT.

Letters Patent No. 71,041, dated November 19, 1867.

IMPROVED SPRING-BUCKLE.

The Schedule referred to in these Letters Patent and making part of the same.

TO ALL WHOM IT MAY CONCERN:

Be it known that I, J. FERGUSON MORSELL, of Stamford, in the county of Fairfield, and State of Connecticut, have invented a new and improved Spring-Buckle; and I do hereby declare that the following is a full, clear, and exact description of the same, reference being had to the accompanying drawings, and to the letters of reference marked thereon.

The nature of my invention consists in a buckle, having a spring attached directly, or otherwise secured, to a bed-plate, and provided with a ridge or jaw, or teeth or the equivalent thereof, so that a strap inserted under such ridge shall be firmly held thereby against any strain tending to pull the strap backward after such insertion. It also consists in the combination with such spring, bed-plate, and jaw, of a loop, which serves as a pulley in tightening the strap, as well as a guide for the latter. In the accompanying drawings—

Figure 1 is a plan or top view, and

Figure 2 is a longitudinal vertical section, taken on the plane of the line xx , fig. 1.

Similar letters refer to like parts in both figures.

A designates a bed-plate or strip of metal, or other suitable material, which may have its upper face flat, as in the present instance, or be furnished with a surface more or less corrugated. To the upper face of this bed-plate there is secured a loop or guide, B, for the strap F; or the said loop or guide B may be part of the same piece of metal as the bed-plate A. On the said loop or guide B the spring C is mounted, being riveted thereto, or otherwise securely fastened. The said spring C, in the present instance, consists of two flat strips of metal, secured at their rear ends to the loop B; but the said spring may be composed of a single strip, of any suitable form. This spring carries upon its under surface a ridge or jaw, D, the front of which has a straight edge, held, when the spring is in its normal condition, in a position close to or nearly against the bed-plate A. Teeth or points may be substituted for the said ridge or jaw D; or the said ridge or jaw D may be serrated or provided with teeth. E designates another loop or guide for the strap F, which guide may be attached to or form part of the bed-plate A, and which is placed in front of the said ridge or jaw D. F designates a leather strap, for the purpose of illustrating the operation of the buckle, such strap being passed through the buckle and the said loop E, its position when held by the buckle being clearly shown in fig. 1.

It may be desirable in some cases to dispense with that part of the bed-plate A directly under the ridge or jaw D, in which case the said ridge or jaw would press the strap against the article (say a trunk) to which the buckle is attached, and the bed-plate A would become simply a frame to support the spring and attach the same to the trunk. In such case the loop E, if used, could be secured to the trunk in front of the spring.

The operation of my invention is as follows: A strap, F, having been passed through the loop B, and under the jaw D, receives at once the pressure of the spring C through the said jaw D. The strap is thus firmly held between the jaw D and the upper surface of the bed-plate A, against slipping, by any strain tending to pull the strap back out of the buckle. The strap can be passed under the loop E, and the said loop E will serve to guide and hold down the strap, and it can be used as a pulley, so to speak, around which the strap can be pulled for the purpose of tightening the same. If necessary to increase the friction of the edge of the jaw or ridge D upon the strap, so as to hold more firmly, this can be effected by cutting slight gashes upon the surface of the strap, as is shown in the present instance, or by using a strap with a corrugated surface; and such cutting of light gashes upon the surface do not injure or weaken a strap so much as does the punching out holes through a strap, which is requisite in the use of the ordinary buckle. To detach the strap from the buckle, the spring C must be raised far enough to allow the strap to be drawn out from under the jaw D; and I will here remark, that any suitable attachment to the spring which can be taken hold of, for readily raising said spring, may be employed.

The advantages which can be obtained by the use of my invention are various. I dispense with tongues, such as are used in ordinary buckles, and "stumps," used in some trace-fastenings, where it is necessary to punch holes in the strap for the reception of such tongues and stumps, and thus limit the points at which the strap can be held by such buckles to the places where holes are punched in the strap. But it may be and usually is desirable that the buckle should be capable of holding the strap, not merely at certain intervals where holes may be punched, but at any place to which it is tightly drawn, which is the case with my invention. Also when

it is necessary, as with buckles on trunks, to frequently require the strap to hold tightly at one particular place in it, the strap being stretched by use, a new place slightly in rear of the other place on the strap must be used to hold with the same tension. But with the ordinary buckle, two holes cannot be punched in the strap close together, as one would be likely to tear into the other, and the strap would, in any case, be greatly weakened. When, also, with an ordinary buckle, a strap has been drawn very tightly and the tongue inserted, it is evident that, to unstrap, the strap must first be drawn just as tight as before, so that the tongue be cleared from its insertion before the tongue can be raised; this is frequently troublesome and difficult, and is not necessary with my invention, for, by raising the spring, the strap is released. The pulley or loop E serves an efficient office for the tightening of the strap, as is evident; but should the loop E be torn away or destroyed, the buckle will still hold the strap in its position.

What I claim as my invention, and desire to secure by Letters Patent, is—

1. The combination of the bed-plate A and spring C, carrying a ridge or jaw, D, substantially as and for the purpose herein specified.
2. The combination of a loop, E, with the bed-plate A and spring C D, substantially as and for the purpose herein specified.

J. FERGUSON MORSELL.
